UNITED STATES PATENT OFFICE

2,484,200

WRIST WATCH

Charles W. Werntz, Huntsville, Mo.

Application July 9, 1946, Serial No. 682,417

3 Claims. (Cl. 224—4)

1

This invention relates to wrist watch straps, and more particularly to a safety bracelet for use with a wrist watch strap to prevent damage or loss of the wrist watch when the strap is accidentally unfastened or when failure of the strap or strap pin occurs without the knowledge of the wearer.

A main object of the invention is to provide a novel and improved safety bracelet for a wrist watch, said bracelet being very simple in construction, easy to attach and attractive in appearance.

A further object of the invention is to provide an improved safety device for a wrist watch which insures against accidental loss or damage to the watch which might otherwise be caused by failure of the main watch strap or its securing pins, said safety device being inexpensive to manufacture and being comfortable to wear.

Further objects and advantages of the invention will become apparent from the following description and claims, and from the accompanying drawings, wherein:

Figure 1 is a perspective view showing a safety device according to the present invention secured in operative position to a man's wrist watch.

Figure 2 is an enlarged cross-sectional detail view showing the method of attachment of the safety device to the wrist watch of Figure 1.

Figure 3 is a perspective view showing a modified form of the safety device of this invention secured to a lady's wrist watch.

Figure 4 is an enlarged perspective detail view of a securing lug employed with the safety device of Figure 3.

Referring to the drawings, 11 designates a conventional wrist watch of the type having securing straps 12 and 13 for securing the watch to the wearer's wrist. According to the present invention, an auxiliary fastening device is provided, said auxiliary device comprising a flexible member 14, such as a metal chain, in the form of a loop loosely secured around the wearer's wrist and having a clasp 15 which engages an eye 16 for detachably fastening the loop ends together. Slidably engaging the flexible member 14 are a pair of lug members 17 and 18, each lug member being formed with a sleeve portion 20 which encircles the flexible member and with a relatively flat eye portion 19 which encircles the strap pin of the watch and is positioned between the edge of the strap loop and the pin lug 21 of the watch, as shown in Figure 2. Although in this figure only the method of connecting the lug member 17 to the strap pin for the strap member 13 is dis-

2

closed, it will be understood that the same method is employed in connecting the lug member 18 to the strap pin for the strap member 12. It will be obvious, therefore, that if either strap member should break or the strap members should be accidentally unfastened unbeknown to the wearer, the watch will remain safely secured to the wearer's wrist by the flexible member 14. The same would be true if either of the strap pins should break. Loss of the watch would, therefore, be prevented, except in the very unlikely circumstance of both strap pins being simultaneously broken without the wearer's cognizance.

Referring to Figure 3, 23 designates a lady's wrist watch provided with a main wrist-engaging chain 24 having a clasp device 25. Encircling the wearer's wrist is an auxiliary flexible member 14 similar to that employed in the embodiment of the invention shown in Figure 1. Member 14 is provided with the respective clasp and eye elements 15 and 16, as in said previous embodiment. Slidably engaging member 14 are a pair of lug members 26, 26, each lug member 26 comprising a major sleeve portion 27 which slidably encircles flexible member 14 and a minor sleeve portion 28 which encircles the side portion of one of the links of flexible member 24. As in the preceding embodiment, if any part of the main securing structure of the watch should fail, the watch will be retained attached to the wearer's wrist by either one or both of the lug members 26, 26 and auxiliary flexible member 14. The same will be true if clasp 25 is accidentally opened unbeknown to the wearer of the watch. Only in the extremely unlikely event of the failure of both lug members 26, 26 would there be any danger of losing the watch.

Auxiliary bracelet member 14, in either of the embodiments herein described, loosely encircles the wearer's wrist and normally is not under stress, the main strap being the normally stressed member.

Minor sleeve portion 28 is bendable so that said minor sleeve position may be readily deformed sufficiently to permit it to be engaged in encircling relation to the link element of chain 24 when the safety device is being secured thereto.

It will be seen that either of the embodiments of the safety device of the present invention may be employed without modification of the wrist watch structures to which they may be secured.

While certain specific embodiments of a wrist watch safety device have been disclosed in the foregoing description, it will be understood that various modifications within the spirit of the in-

vention may occur to those skilled in the art. Therefore, it is intended that no limitations be placed on the invention other than as defined by the scope of the appended claims.

What is claimed is:

1. A safety bracelet for use with a wrist watch band comprising a flexible member arranged as a loop, and a pair of spaced lugs positioned adjacent said flexible member and said band and operatively connected to said band, each of said lugs encircling said flexible member and slidably engaging the latter.

2. A safety bracelet for use with a wrist watch strap comprising a flexible member arranged in a loop, and a pair of spaced lugs positioned adjacent said flexible member and said strap, each of said lugs having a flat end portion associated with said strap, the other end of each of said lugs having a sleeve therein encircling said flexible member and slidably engaging the latter member.

3. A safety bracelet for use with a chain wrist

watch band comprising a flexible member arranged in a loop, and a pair of lugs positioned adjacent said flexible member and said chain wrist band, each of said lugs having one end carried by a link of said chain wrist band and having the other end encircling said flexible member and slidably engaging the latter member.
